Des. 236,681
Patented Sept. 9, 1975

236,681

PAIR OF SCISSORS

Salvatore J. Megna, Sacramento, Calif., assignor to
Professional Instruments, Incorporated, Cincinnati,
Ohio

Filed Nov. 19, 1973, Ser. No. 417,040

Term of patent 14 years

Int. Cl. D8—03

U.S. Cl. D8—57

FIG. 1 is an elevational view of a pair of scissors showing my new design;

FIG. 2 is an end elevational view taken from the blade end of the scissors;

FIG. 3 is an end elevational view taken from the handle of the scissors;

FIG. 4 is a top plan view taken from the upper side of FIG. 1;

FIG. 5 is a bottom plan view taken from the lower side in FIG. 1; and

FIG. 6 is an elevational view showing the side opposite to that shown in FIG. 1.

I claim:

The ornamental design for a pair of scissors, substantially as shown and described.
